ATTACHMENT FOR SEWING MACHINES

John D. Karle, Roselle Park, N. J., assignor to
The Singer Manufacturing Company, Elizabeth, N. J., a corporation of New Jersey

Application December 20, 1934, Serial No. 753,381

6 Claims. (Cl. 112—160)

This invention relates to attachments for sewing machines and more particularly to attachments for vibrating the work relative to the needle and laterally of the line of seam formation to produce zigzag stitches.

The several features of the present invention will be clearly understood from the following description and accompanying drawings in which:

Figure 1 is a front elevation showing a portion 10 of a sewing machine with my improved attachment fixed thereto.

Figure 2 is a rear elevation.

Figure 3 is a side elevation looking from the right of Figure 1.

15 Figure 4 is a top plan view.

Figure 5 is a disassembled perspective view of the pawl and two-part needle-bar actuated lever.

My improved attachment is shown applied to a well known "Singer" family type machine having the usual spring-pressed presser-bar 1, reciprocating needle-bar 2, needle-clamp 3, needle 4, and feed-dog 5.

In its preferred embodiment the attachment comprises a channel block 6 adapted to be secured by the fastening screw 7 to the lower portion of the presser-bar 1. Carried by the block 6 is a plate 8 having an upstanding inclined arm 8' and a cross arm 9 formed with elongated apertures 10 and outwardly projecting lips 11 which form a guiding channel. Slidably held in the guiding channel by the rivets 12 is a bar 13 having a depending portion 14 to which is secured by means of the screw 15 a presser-foot 16 formed with an elongated needle-aperture 16'.

35 Pivotedly secured to the upstanding arm 8' of the plate 8 by the pivot-pin 17 is a swingable member 18 having a laterally extending portion 19 provided with a stud 19'. The swinging member 18 has an opening 24 with inwardly extending projections 25 and 25' adapted to embrace and engage a cam element 26 having a plurality of circumferentially spaced projections. Fixed to the cam-element 26 is a ratchet-wheel 28, and the cam-element and ratchet-wheel are rotatably 45 mounted on the plate 8 by means of a bearing pin 29.

Pivotedly secured to the arm 8' by the pivot-pin 30 is a lever 31 (Fig. 5) formed with an apertured free end 32, a forwardly extending arm 33 and a rearwardly extending arm 34. A lever 35 having a forwardly extending lip 36 and a rearwardly extending portion 37 is pivotally secured to the end 32 of the lever 31 by the internally threaded pivot-stud 38 on the pawl 39 (Fig. 5). 55 It will be understood that the stud 38 passes

through the aperture 40 in the lever 35 and the aperture 40' in the lever 31 and is held in position by the screw 41. A helically wound spring 42 reacts between the arm 33 on the lever 31 and the pawl 39 to constantly urge the pawl in a clockwise direction about its pivot-stud 38.

A spring 43 embraces the spacing sleeve 44 and has one of its ends acting against the arm 8' and its other end against the portion 37 of the lever 35. The spring 43 urges the lever 35 in a clockwise direction about its pivot, the movements being limited by the nose 45 on the lever 35 which engages the rearwardly extending arm 34 on the lever 31. The spring 43 also urges the levers 31 and 35 and the pawl 39 in a counter-clockwise direction about the pivot-pin 30, this movement being limited by the arm 34 which engages the arm 8'. From the foregoing it will be observed that the levers 31 and 35 are in effect a two-part pawl-carrying lever.

20 A finger-lever 46 is provided for rendering the attachment inactive at the will of the operator. This expedient is shown and described in Patent No. 2,003,200, dated May 28, 1935.

Made integral with the cross-arm 9 is an up-standing arm 47 having a bell-crank lever 48 pivotally secured to its upper end by the pivot-pin 49. One arm of the bell-crank lever is bifurcated to receive the stud 19' carried by the swingable member 18 and the other arm is formed with an arcuate slot 50. A pitman 51 connects the bell-crank lever 48 to the slide-plate 13 and has one of its ends adjustably secured in the slot 50 by the screw 52 and its other end pivotally secured by the pivot-pin 53 to the slide-plate 13.

Operation

On the upward movement of the needle-bar, the needle-clamp 3 engages the projection 36 on the lever 35 and moves the lever 31 and pawl 39 upwardly. During the movement the pawl 39 engages the ratchet-wheel 28 and advances it one step or one-eighth of a revolution, it being understood that the distance the pawl travels on each upstroke of the needle-bar is slightly greater than the distance between the teeth on the ratchet-wheel. The cam-element 26 being fixed to the ratchet-wheel 28 is also moved one-eighth of a revolution. The rotation of the cam-element causes one of its circumferentially spaced projections to contact the inwardly extending projections 25 on the swinging member 18 causing it to swing in a clockwise direction about its pivot 17. This swinging movement causes the pin 19' to swing the bell-crank lever 48 in a counter-clock-

wise direction about its pivot 49. This motion is imparted to the slide-plate 13 by means of the pitman 51 thereby causing the presser-foot 16 to move to the left to the position shown in Fig. 1. 5
5 The shifting of the presser-foot 16 occurs while the usual feed-dog 5 is below the throat-plate 55 and is completed just prior to the point of the cycle when the feed-dog contacts the work. After the feed-dog 5 has advanced the work, the needle 10 descends, forming the stitch and on the upstroke of the needle, the needle-clamp 3 again engages the forwardly extending portion 36 of the lever 35 and moves the lever 31 and pawl 39 in a counter-clockwise direction about the pivot 30, the 15 pawl again advancing the ratchet-wheel one-eighth of a revolution. This movement of the ratchet-wheel causes the cam 26 to shift the swingable member 18 in a counter-clockwise direction about its pivot and this movement is imparted to the slide-plate 13 by means of the pin 19', bell-crank lever 48 and pitman 51. The slide-plate 13 and presser-foot 16 are thereby shifted to the right. From the foregoing it will be observed that in the rotation of the cam-element 25 26, its peripheral projections successively engage the projections of the swinging lever 18 to vibrate the same and thus reciprocate the slide-plate and presser-foot laterally of the line of seam formation. It will be obvious that the amount of movement of the slide-plate 13 may be varied by adjusting one end of the pitman 51 in the arcuate slot 50 of the bell-crank lever 48.

This construction provides an adjustment for varying the lateral shifting movement imparted 35 to the presser-foot which can be quickly and easily made and translates the arcuate movement of the pin 19' to a right line movement without using a lost motion connection between the swinging member 18 and sliding plate 13, thereby reducing the operating noise of the attachment by 40 eliminating the "hammer" blow. Further, overthrow of the presser-foot under speed is prevented.

It has been found that when an attachment of 45 this type is fixed to the presser-bar with the needle-bar clamp in its highest position, the lip 36 on the pawl-carrying lever is disposed beneath the needle-clamp with the result that, upon operation of the machine, the needle-clamp on its 50 down stroke will strike the lip 36 and damage the attachment. To overcome this difficulty, the pawl-carrying lever is made in two parts (31 and 35) which are pivoted together and the lever 35, which is engaged by the needle-bar clamp, is 55 spring-urged about its pivot in a clockwise direction by the spring 43 and its movement is limited by the stop 45 and arm 34.

With this arrangement, if the attachment is inadvertently attached to the machine with the 60 end of the pawl-carrying lever in a position to be engaged by the needle-clamp on its downward stroke, upon operation of the machine the free end of the lever 35 will yield to permit the initially descending needle-clamp to pass. After the 65 needle-clamp has passed, the lever will assume its operative position due to the influence of the spring 43.

Having thus set forth the nature of the invention, what I claim herein is:—

70 1. A zigzag-stitching attachment comprising a member adapted to be secured to the presser-

bar of a sewing machine, a frame carried by said member, a slide-plate carried by said frame, a swingable member carried by said frame, a cam for vibrating said member, ratchet and pawl means for actuating said cam, a bell-crank lever 5 pivoted to said frame and actuated by said swingable member and means for connecting said bell-crank lever to said slide-plate.

2. A zigzag-stitching attachment comprising a member adapted to be secured to the presser-bar 10 of a sewing-machine, a frame carried by said member, a slide-plate carried by said frame, a swingable member pivoted to said frame, a cam for vibrating said member, ratchet and pawl means for actuating said cam, a bell-crank lever 15 pivoted to said frame and actuated by said swingable member and a pitman having one of its ends 20 adjustably connected to one of the arms of said bell-crank lever and its other end pivotally connected to said slide-plate.

3. A zigzag-stitching attachment comprising a member adapted to be secured to the presser-bar of a sewing machine, a frame having an up-standing arm and a cross-arm formed with a channel secured to said member, a slide-bar carrying a presser-foot fitted in said channel, a swinging lever fulcrumed on the up-standing arm of said frame, a cam pivoted to the up-standing arm of said frame for actuating said swinging lever, means for actuating said cam, an up-standing arm carried by the cross-arm of said frame, a bell-crank lever pivoted to said arm and having one of its arms operatively connected to said swinging lever and a pitman connecting said slide-bar to the other arm of said bell-crank 25 30 35 lever.

4. An attachment for sewing machines having a vibratory work-engaging member and means for vibrating said member, said means including a cam, and a ratchet and pawl for actuating said 40 cam, said pawl being carried by a two part pivoted lever composed of relatively yielding parts.

5. In combination with a sewing machine having a needle-bar and a presser-bar, a frame secured to said presser-bar, a slide-plate carrying a 45 presser-foot mounted on said frame, a swingable member pivoted to said frame, a cam for actuating said member, and means for actuating said cam, said means comprising a ratchet fixed to said cam, a lever pivoted to said frame, a second 50 lever pivoted to the first mentioned lever and having a stop to limit its movement in one direction relative to the first mentioned lever, a spring for yieldingly urging said second lever against said stop, and a pawl carried by said lever for 55 actuating said ratchet-wheel.

6. An attachment comprising a frame adapted to be secured to the presser-bar of a sewing machine, a slide-plate and presser-foot carried by said frame, a swingable member pivoted to said frame, a bell-crank lever actuated by said swingable member, a connection between the bell-crank lever and said slide-plate, a cam in operative engagement with said swingable member, a ratchet-wheel carried by said cam, a needle-bar 60 actuated two-part lever pivoted to said frame and having a yieldable free end and a pawl carried by said lever for imparting a step-by-step movement to said ratchet-wheel.
